FOLKE FRED NORDEN, OF BROOKLYN, AND WALTER GILSON LOAN, OF ST. GEORGE, NEW YORK.

LEGGING.

Application filed February 17, 1927. Serial No. 169,036.

Our invention relates particularly to leggings for women and others, whose legs are at the present time unprotected from the elements, splashing of mud etc., and the objects 5 of our invention are to provide leggings which can be quickly and easily applied and secured to and removed from the legs and feet, will easily adapt and adjust themselves to legs of any size and length, will effectively protect the legs and feet from cold and the elements and from mud splashed by automobiles, and when removed can be quickly and easily folded into a small compass and packed in a small space such as a hand bag 15 for transportation. To these and other ends our invention consists of a flexible canvas leather or other suitable covering, preferably waterproof, secured upon an openable wire frame or series of members which can be 20 quickly applied to and will fit, adjust and secure themselves to any size leg and foot, and when removed can be collapsed with the covering into a small compass and packed in a small space.

25 Our invention also consists in making the frame or members of a continuous piece of resilient wire.

Our invention also consists in providing the openable wire frame members with interlocking and sliding connections along the leg portion the better to prevent the frame from becoming separated from the leg and to permit the members to adjust themselves to the leg. Our invention also consists in 30 providing the wire frame with extensions to project under the sole of the shoe and around the heel to hold the foot portion of the legging in place on the shoe.

In order that our invention may be fully 40 understood, we shall first describe in detail the mode in which we at present prefer to carry the invention into practice and then particularly point out its novel features in the claims.

45 Reference is to be had to the accompanying drawings forming part of this application in which like parts are designated by the same numbers in all the figures.

Figure 1, is a side elevation of a legging 50 embodying our invention applied to a woman's leg and shoe, part of the covering being removed to show the construction and application of the frame. Figure 1^a is an enlarged view of a detail.

Figure 2, is an inverted plan view of the 55 same.

Figure 3, shows the legging collapsed around the ankle.

Figure 4, shows the legging collapsed for 60 packing, part of the covering being removed to disclose the frame and extensions.

In the specific embodiment of our invention shown in the drawings, 4 designates the covering, which may be of leather, waterproofed canvas, or other suitable material, 65 and 5 designates the collapsible frame of the legging.

We prefer to form the frame 5 of a single piece of resilient rust-proof wire bent to 70 form a vertical series of nearly circular elastic clamp-like members 6 each opening and separable preferably at the side to receive and embrace tightly the leg of the wearer.

The adjoining ends 7 and 8 of each member 6 overlap and a short headed post 9 formed on one end of each member is caught but rides adjustably lengthwise between the parallel wire elements forming a 75 loop 10 on the other end of said member. 80 The various members 6 are thus prevented from becoming detached from the leg of the wearer, when fastened together thereon as shown and described, and yet can fit and adjust themselves to legs of various sizes. 85

The wire of the lowermost leg member 6 is preferably extended to form a heel-clamping member 11, to embrace the back of the heel of the shoe and shoe embracing members 12, which extend transversely over 90 the top of the shoe, downward on each side and a short distance under each side of the shoe sole, so that the shoe portion 13 of the legging carried thereby can be clamped removably around the heel and toe of the 95 shoe.

The covering 4 of the legging may be secured to the wire frame 5 and extensions 11 and 12, by stitches as shown or in any other approved way. The legging thus applied 100 will completely cover the leg and shoe of the wearer and protect it from the elements, mud splashes, etc.

When the legging is not needed for protection the several leg members 6 with the 105 covering can be closed up around the ankle of the wearer, as illustrated in Figure 3, or by disconnecting the leg members 6 and

unclamping the heel and toe extensions 11 and 12, the legging can be removed from the leg and shoe and collapsed as shown in Figure 4 for convenient packing and transportation.

It is evident that the adjoining or overlapping edges of the covering 4 may be fastened together by snaps or other fasteners as desired, and that ordinary straps 10 extending under the arch of the shoe may be used if desired to keep the legging from riding up the leg.

It is evident that many changes may be made in the details of construction and arrangement here illustrated without departing from the boundaries of our invention as defined by the following claims.

We claim as our invention:

1. A legging comprising a flexible covering and a vertical series of openable resilient leg-embracing members attached thereto and a slide on one end of each resilient member, playing in a guide on the other end of said member.
2. A legging comprising a flexible covering and a vertical series of openable resilient leg-embracing members attached thereto, one end of each leg member being formed with a guide post and the other end with a guide in which the guide post is held and can slide to adjust the member to the size of the leg.
3. A legging comprising a flexible cover-

ing and a vertical series of openable resilient leg-embracing members attached thereto, one end of each leg member being formed with a headed guide post and the other end with a guide in which the headed guide post is held and can slide adjustably.

4. A legging comprising a flexible leg and shoe covering, a vertical series of openable resilient leg members attached to the leg covering and a series of openable resilient foot members attached to the shoe covering to embrace the toe portion of the shoe.

5. A legging comprising a flexible leg and shoe covering, a vertical series of openable resilient leg members attached to the leg covering, and a series of openable resilient foot members attached to the shoe toe covering to embrace the toe portion of the shoe and an openable resilient heel member attached to the heel covering to embrace the heel of the shoe.

6. A legging comprising a flexible leg and shoe covering and a resilient wire frame attached thereto consisting of a connected series of openable resilient leg, toe and heel embracing members all collapsible with the covering into a substantially flat bunch or package around the ankle or for transportation.

In testimony whereof we affix our signatures.

FOLKE FRED NORDEN.
WALTER GILSON LOAN.
